UNITED STATES PATENT OFFICE.

ANDREW J. RUSSELL AND WILLARD B. TERRY, OF STURGIS, MICHIGAN.

SLIDING GATE.

No. 885,085.

Specification of Letters Patent.

Patented April 21, 1908.

Application filed January 11, 1908. Serial No. 410,393.

To all whom it may concern:

Be it known that we, ANDREW J. RUSSELL and WILLARD B. TERRY, citizens of the United States, residing at Sturgis, in the 5 county of St. Joseph and State of Michigan, have invented a new and useful Sliding Gate, of which the following is a specification.

This invention relates to sliding gates and more particularly to means whereby a gate 10 of this character can be operated by a person seated within a vehicle adjacent thereto, the operating mechanism being simple, durable and efficient and of such character that it can be readily placed in position.

15 Another object is to provide mechanism of this character in which friction is reduced to the minimum, thus proportionately facilitating the action of the parts.

With these and other objects in view the 20 invention consists of certain novel features of construction and combinations of parts which will be hereinafter more fully described and pointed out in the claims.

In the accompanying drawings is shown 25 the preferred form of the invention.

In said drawings: Figure 1 is a perspective view of the gate. Fig. 2 is an enlarged section on line $x-x$, Fig. 1. Fig. 3 is an enlarged section on line $y-y$, Fig. 1.

30 Referring to the figures by characters of reference, 1 designates a standard constituting one of the gate posts and 2 constitutes the other gate post, the same being preferably formed with parallel retaining 35 cleats 3 between which the end of the gate is designed to extend when closed. Secured to the standard 1 and to one or more fence posts 4 disposed in the rear thereof or beyond it is a supporting beam 6 having a plurality of outstanding studs 6 to which is bolted or otherwise fastened an elongated metal strip 7 constituting the rail used for supporting and guiding the gate.

40 The gate may be of any preferred construction and the top rail thereof preferably extends beyond one end of bar 9 of the gate to form an arm 10. This arm may be provided with a brace 11 so as to hold it rigidly beyond the gate. Secured to the rail 8 adjacent the upper end of the bar 9 is a yoke 12 the lower end of which extends at right angles therefrom as indicated at 13 and un-

der the rail 8. This yoke is fastened to said rail in any preferred manner as by means of screws or bolts and carries a sheave 14 designed to bear upon the rail 7. A retaining finger 15 is struck from the lower portion of yoke 12 and extends under the rail so as to prevent the sheave from lifting therefrom. The construction of these parts has been 55 clearly indicated at Fig. 2. Secured to the rear portion of the arm 10 is an inverted yoke 16 somewhat similar to yoke 12, the upper end thereof being bent over the arm 10 as shown at 17 in Fig. 3. A sheave 18 is 60 mounted in this yoke and designed to bear upward against the lower edge of the rail 7 and a retaining pin 19 extends from the arm 10 and over the rail so as to prevent said arm from moving downward in relation to 65 the rail.

Arranged longitudinally upon the top rail of the gate 8 is a slotted retaining strap 20 and extending loosely through this strap is the upper portion of an operating lever 21, 75 the lower end of which is pivotally connected to a base block 22 extending laterally from the lower portion of the standard 1 and under the gate, said block being preferably recessed in its upper face as shown at 23 so 80 as to guide the lower portion of the gate in its movements. A weight 24 is secured to the upper end of the lever 21 and extending from said lever at an intermediate point is a link 25. A push bar 26 is pivotally connected to lever 21 close to the weight 24 and above strap 20 and is also pivotally connected to the upper portion of the end bar 9 of the gate.

85 A beam 27 is mounted upon the upper end 90 of standard 1 and at right angles to the gate and secured to this beam directly above the gate is a guide plate 28 having openings 29 therein designed to receive chains, cables, or other flexible devices 30 extending in opposite directions from sheaves 31 mounted upon the beam and above plate 28. These flexible devices 30 extend longitudinally of the beam and over sheaves 32 disposed adjacent the ends thereof and the terminals of the flexible 95 devices extend downward through apertured guide plates 33 and are provided with weights 34 whereby said devices are held normally taut. A flange 35 is preferably 100

formed along the upper portion of the beam 27 and overhangs the sheaves so as to shield the sheaves and the parts mounted thereon.

Should the gate be closed the same can be

- 5 readily opened by pulling downward either one of the weighted chains or cables 30. This will cause link 25 to pull up lever 21 and when said lever assumes a vertical position it will be swung by gravity downward 10 and away from the post 2. As the lever is connected to the gate by means of link 26 this operation thereof will cause the link to push the gate longitudinally and the two sheaves 14 and 18 will travel along rail 7 and 15 permit the gate to move with little friction. To close the gate either chain or cable 30 is again pulled downward with sufficient force to swing lever 21 back to its original position, this operation of the lever pulling on the link 20 26 so as to slide the gate into closed position. Importance is attached to the fact that motion is transmitted from the lever to the gate through a push bar or link 26 because the elimination of a vast amount of friction thus 25 results and the operation of the gate is rendered more easy and efficient than where the lever is utilized to bear directly against a portion of the gate as heretofore.

It will be noted that it is not necessary

- 30 with this apparatus to provide a gate of complicated construction. As a matter of fact the operating mechanism can be readily applied to any ordinary sliding gate simply by providing an arm 10 at one end thereof and 35 applying to the gate the various parts of the apparatus, none of which necessitates the changing structure of the gate. The beam 5

not only serves to support the rail 7 but also acts as a brace connecting the standard 1 with one or more fence posts.

40

What is claimed is:

1. The combination with a standard and a rail extending beyond it; of a sliding gate supported by the rail, a weighted actuating lever having a fixed pivot, a link pivotally connected at its ends to the lever and gate respectively, a beam supported by the standard and at right angles to the gate, sheaves thereon, flexible means supported by the sheaves and connected to the lever for shifting said lever past its center of gravity to move the gate into open or closed position, and a shield upon the beam and overhanging the sheaves and the flexible means thereon.

45

2. The combination with a standard and a rail extending therebeyond; of a sliding gate supported by the rail, a longitudinal retaining device upon the gate, an actuating lever having affixed pivot, said lever extending loosely between the gate and the retaining device, a weight at the free end of said lever, a link pivotally connected at its ends to the lever and gate respectively, and means carried by the standard for actuating the lever to swing the weight past its center of gravity 60 to move the gate into open or closed position.

55

In testimony that we claim the foregoing as our own, we have hereto affixed our signatures in the presence of two witnesses.

ANDREW J. RUSSELL.
WILLARD B. TERRY.
